[57] CLAIM

The ornamental design for a mobile radio housing, as shown
and described.

DESCRIPTION

FIG. 1 is a top plan view of a mobile radio housing showing
our new design;

FIG. 2 is a right side elevational view thereof the left side
view being a mirror image;

FIG. 3 is a bottom plan view thereof;

FIG. 4 is a rear elevational view thereof; and,

FIG. 5 is an isometric view thereof.

The broken line showing of the mobile radio control head
portion in FIGS. 1-3 and 5 is for illustrative purposes only
and forms no part of the claimed design.
